UNITED STATES PATENT OFFICE.

CARL R. LENDLE, OF CHICAGO, ILLINOIS.

SKIRT-HANGER.

1,247,551.

Specification of Letters Patent. Patented Nov. 20, 1917.

Application filed October 25, 1916. Serial No. 127,666.

To all whom it may concern:

Be it known that I, CARL R. LENDLE, a citizen of the United States, residing at Chicago, in the county of Cook and State of Illinois, have invented new and useful Improvements in Skirt-Hangers, of which the following is a specification.

This invention is an improved hanger for skirts and the like, the object of the invention being to provide an improved device of this character which is simple in construction, is light, strong and durable and which is variable in length and automatically adjusts itself to the width of the skirt or other garment hung thereon.

The invention consists in the construction, combination and arrangement of devices hereinafter described and claimed.

In the accompanying drawings:

20 Figure 1 is partly an elevation and partly a sectional view of a skirt hanger constructed and arranged in accordance with my invention.

Fig. 2 is a plan of the same.

25 Fig. 3 is a transverse section of the same on the plan indicated by the line 3—3 of Fig. 1.

In the construction of my improved skirt and coat hanger I provide a pair of tubes 20 1, 2 of suitable length and diameter and which in practice may be made of cheap sheet metal. The tube 1 is telescopically arranged in the tube 2 so that the bar formed by the said tubes is adjustable longitudinally 35 and adapted for use in hanging a skirt or coat of any width. Each of the tubes is provided in its upper side with a longitudinal slot 3. Said slots are open at the outer ends of the tubes. Tube 1 is provided at its 40 inner end with a collar 4 which forms a stop and closes the corresponding end of the slot 3 of said tube. The tube 2 has a collar 5 at its inner end which forms a stop and closes the inner end of the slot 3 of said tube.

45 A block 7 is secured to and closes the outer end of each tube. Each of the said blocks is made of sheet metal and is substantially U-shaped in plan, providing an outer face 8 adapted to engage the garment and also 50 providing a pair of sides or walls 9 on opposite sides of the tube. The face 8 is roughened as at 10 to engage the garment and

each block is provided with a downwardly and outwardly extending arm 11, shaped to correspond apportionately with that portion 55 of the garment engaged with the hanger. Each arm 11 is made of a piece of U-shaped wire as here shown.

The tubes 1, 2 being telescopically related, the bar which is formed by said tubes is 60 longitudinally adjustable and hence the hanger may be adjusted in length according to the width of the garment to be hung thereby. A coil extensile spring 12 extends longitudinally through the tubes 1, 2, its 65 ends bearing against the blocks. The central portion of the coil spring is engaged by the inturned end 13 of a connector 14 which is here shown as made of iron and which passes around the tube 2 and is 70 formed at its upper end with an eye 15 which is engaged by a suspending hook 16. The arm 13 of the connector passes through and is arranged to operate in the slots of the tubes. The spring acts to longitudinally 75 extend the hanger or the bar formed by the tubes thereof by permitting the hanger to be shortened as required by the garment. The arm 13 coacts with the collars 4, 5 to form stops which limit the extent of outward movement of the tubes.

80 While I have herein shown and described a preferred form of my invention I would have it understood that changes may be made in the form, proportion and construction of the several parts without departing from the spirit of my invention and within the scope of my claim.

Having thus described my invention, what I claim is:

85 A longitudinally adjustable hanger of the class described comprising a pair of telescopically arranged tubes, one slideable longitudinally in the other and a coil spring in said tubes and connected thereto to normally hold the hanger in extended condition, each 90 of the said tubes being provided with a longitudinal slot, said slots being coincident with each other, and a suspending device for the hanger attached to the outer tube having 95 an arm extending through said slots and engaging the central portion of said spring.

100 In testimony whereof I affix my signature.
CARL R. LENDLE.
